UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

LOADING MACHINE

Application filed March 15, 1922, Serial No. 543,933. Renewed October 20, 1928.

The present invention relates to certain new and useful improvements in loading machines, and particularly to that class of loading machines which is adapted to use in coal mines to gather the dislodged material from the floor of the mine and load it into suitably positioned cars for transportation from the mines.

The especial object of this invention is to provide a machine of the class described, having improved gathering devices adapted to positively engage the interlocked fragments of material upon the floor of the mine, tear them loose from the mass of such fragments and load them into the conveyor.

Another object is to provide improved mechanism for feeding the gathering mechanism to the material which is to be loaded.

Another object is to provide improved means to adjust the gathering and loading mechanism in vertical planes.

Another object is to provide improved mechanism for propelling the machine along the tracks of the mine from one working place to another.

These and other objects will appear in the following specification, reference being had to the accompanying drawings of which

Fig. 1 is a side elevation of the preferred embodiment of my invention, adjusted to operative loading position.

Fig. 2 is a side elevation of the machine illustrated in Fig. 1, adjusted to traveling position.

Fig. 3 is a plan view of the machine illustrated in Figs. 1 and 2.

Fig. 4 is a sectional view taken along the line IV—IV of Fig. 1.

Fig. 5 is a sectional view taken along the line V—V of Fig. 3.

Fig. 6 is a sectional view taken along the line VI—VI of Fig. 3.

Fig. 7 is a sectional view taken along the line VII—VII of Fig. 6.

Fig. 8 is a sectional view taken along the line VIII—VIII of Fig. 9.

Fig. 9 is a sectional view taken along the line IX—IX of Fig. 3.

Fig. 10 is a front elevation of some of the parts shown in Fig. 3.

Fig. 11 is a fragmentary, somewhat diagrammatic figure illustrating the mechanism by which the gathering devices are fed to the material to be loaded.

Fig. 12 is a fragmentary plan view of the supporting truck illustrating the conveyor adjusting and truck propelling mechanisms.

Fig. 13 is a sectional view taken along the line XIII—XIII of Fig. 3.

Figs. 14, 15 and 16 are diagrammatic figures illustrating the method of operating my improved loading machine in a room of a mine.

Like numerals refer to similar parts in the several figures.

As shown in the drawings, my improved loading machine comprises an elongated conveyor having a substantially horizontal gathering section adapted to rest upon and slide over the floor of the mine to gather material therefrom, a rearwardly and upwardly inclined portion and a substantially horizontal delivery portion adapted to project above a car suitably positioned upon the track in the rear of the machine. The conveyor above described is mounted upon a truck adapted to travel along the rails of the track, and these parts are associated with power actuated mechanism to move the conveyor along horizontal lines and to adjust it in vertical planes.

In the drawings, the numeral 1 refers to the main truck frame upon which the conveyor is supported, and the numerals 2 and 3 refer to the wheels upon which the truck frame is supported for transportation from one working place to another. Fixed to the rear part of the truck frame are two upstanding pedestals 4, in each of which there is journaled a vertical shaft 5. Formed on the shafts 5 are screw threads which engage the nuts 6 upon which rest the ends of the downwardly projecting legs 7, formed integral with the cross bar 8 and constituting a supporting frame on which the conveyor frame is laterally slidable transversely of the machine. The nuts 6 are slidable in guideways of the pedestals 4 and move upwardly or downwardly in said guideways when the shafts 5 are rotated. On the lower ends of the shafts 120

5 are mounted sprocket wheels 9 which are adapted to be connected with their respective shafts by the clutch members 10, and operating handles 11 are arranged within convenient reach of the operator for the manipulation of these clutches. An endless chain 12 passes around the sprocket wheels 9 and after passing around suitable guide wheels 13 fixed to the truck frame, is engaged by the sprocket 10 wheel 14. The sprocket wheel 14 is attached to the lower end of the vertical shaft 15 which is supported in suitable bearings of the housing casting 16, and has at its upper end a bevel gear wheel 17. The wheel 17 is engaged 15 by a bevel pinion 18 attached to a horizontal shaft 19 supported in bearings of the housing 20 16. The shaft 19 is in alignment with a shaft 20 journaled in bearings of the gear housing 21, and is connected thereto by a jaw 25 clutch 22 of well known construction.

Mounted upon the shaft 20 is a sleeve 23 to which is keyed the worm wheel 24. The worm wheel 24 is engaged by a worm 25 supported in bearings of the gear housing 21 and connected directly to the armature shaft 26 of the motor 27. A multiple disc friction clutch 28 is arranged to connect the worm gear 24 with the shaft 20, and an operating lever 29 is arranged to control the actuation 30 of the clutch in the manner well understood in the art. A sprocket wheel 30, mounted upon the shaft 20 and connectable thereto by the clutch 31, is connected by the endless chain 32 with a similar sprocket wheel 33 fixed to the axle 34 to actuate the driving wheels 2 to propel the machine along the rails 35 of the mine tracks. Interlocking clutch shifting mechanism is provided in the rod 36 and shift levers 37 and 38 to control the 40 clutches 22 and 31 and prevent the actuation of the truck driving mechanism and the conveyor adjusting mechanism at the same time. Electric current for the actuation of the motor 27 is derived from the feeder wires of the mine through a flexible cable 39 which is arranged to be automatically payed out from, or wound upon a cable reel 40 in the manner which is well understood in the mining art. An endless belt 41 engages the pulley 42 upon 50 the cable reel, and the pulley 43 upon the shaft 20 to supply power for the actuation of the cable reel. The motor 27 may be controlled in any preferred manner, but as devices of this class are well understood, and 55 as they form no part of the present invention, their illustration and description is not thought to be required.

Extending transversely of the truck frame 1 at its forward end is an arcuate rail 44 upon which is slidably supported for longitudinal movement a bearing member 45 attached to the conveyor frame and upon which said frame may rock in any direction. The bearing member 45 is in the nature of a block 65 attached to the conveyor frame and having

its contact face with rail 44, appropriately shaped to permit the rocking of the frame. This arcuate rail 44 projects at both sides of the truck frame for a purpose which will presently appear.

The conveyor comprises an elongated frame, designated as an entirety by the numeral 46. This frame consists of a pan 47 having flaring side walls 48 and which is divided into two parallel troughs by the two parallel longitudinally extending chain guides, each of which consists essentially of the upper angle bar 49 and the lower angle bar 50, (see Figs. 7 and 8), in which travels the endless conveyor chain 51. On certain 70 of the chain links there are formed sockets 52 in which are secured the renewable cutter bits 53 of the type commonly used with the cutter chains of coal mining machines. These sockets 52 and the bits 53 project laterally from the chain and constitute the material propelling element of the conveyor.

The pan parts 47 and the angle bars 49 and 50 are connected together by various transverse bars, plates and castings to form a rigid structure. Attached to the rearward ends of the angle bars 49 and 50 is a casting 54 upon which is formed a guideway 55, and upon this guideway is slidably mounted for movement longitudinally of the conveyor 80 frame, a bearing casting 56 in which is journaled the vertical head shaft 57. To the head shaft 57 is attached a sprocket wheel 58 which is adapted to engage the conveyor chain 51 and to turn it around the rearward end of the conveyor frame. Attached to the vertical shaft 57 is a bevel gear wheel 59 which is engaged by a pinion 60 fixed to the longitudinally extending shaft 61 to drive the sprocket wheel 58 and actuate the conveyor 90 chain 51. The shaft 61 is supported in suitable bearings attached to the conveyor frame, and has fixed to its forward end a sleeve 62 on the end of which is formed clutch teeth adapted to engage with the corresponding 100 teeth of the clutch member 63 which is slidably upon the power shaft 64, from which power is derived to actuate the conveyor. Means is provided in the adjusting screw 65 to move the bearing casting 56 to tension the 110 chain 51 in the manner common in conveyor practice.

Formed on the casting 56 concentric with the shaft 57 is a downwardly projecting pivot stud 66 which engages with a bearing socket 67 formed at the outer end of the pivot yoke 68. The pivot yoke 68 is hinged to the lugs 69 formed on the cross bar 8, and serves to hold the delivery end of the conveyor in a position central of the track to deliver material to a car 70 standing thereon adjacent the rearward end of the machine, while permitting sufficient flexibility in vertical planes for the vertical adjustment of the conveyor. A machine screw 71 which projects through a 120

suitable aperture in the socket casting 67, and is tapped into the pivot stud 66, serves to hold these parts in operative relation.

At the lower end of the frame 46 is secured 5 a casting comprising essentially an upper wall 100 and lateral walls 101 and 102 (see Figs. 8 and 9.). A pivot pin 73 is disposed in aligned apertures in walls 101 and 102 and passes through an aperture formed in the 10 central cylindrical portion 103 of a casting 104. The casting 104 has rearwardly extending vertical flanges 105 joined by a web 106, and to the forward portion of the casting is secured an extension frame 74 in the nature 15 of a gathering frame and cutter arm. The bottom of casting 104 is provided with a shoe 72 adapted to rest on and slide over the floor of the mine, supporting the weight of the front end of the conveyor if the latter has 20 been elevated sufficiently on cross member 8 to disengage members 44 and 45.

The gathering frame 74 is adapted to rest upon and slide over the floor of the mine, and the connection with the pivot pin 73 affords 25 sufficient flexibility to allow it to follow the irregularities of the floor of the mine. The pivot 73 also permits the rear end of the conveyor to be vertically adjusted without effecting the horizontal position of gathering 30 frame 74. While frame 74 is pivoted to frame 46 for free pivotal movement, it will be noted that this movement will be limited in one direction by reason of the abutment of flanges 105 with wall 100. Thus when the main 35 frame 46 is tilted as in Fig. 2 the gathering frame will be bodily elevated clear of the floor. The gathering frame 74 is provided with lateral chain guides registering with the chain guides of the conveyor frame 46, and 40 at its forward end there is mounted upon a suitable anti-friction bearing 75, a sprocket wheel 76 which engages the conveyor chain 51 to turn it around the end of the frame with a minimum of frictional resistance. As there 45 is no trough along either side of the gathering frame 74, the lateral projections of the conveyor chain are in position to engage with material lying upon the floor of the mine, and drag it into the trough of the inclined portion 50 of the conveyor.

Mounted upon the power shaft 64 and operatively connected therewith, is an eccentric 77 having an eccentric rod 78 connected to a cross head 79 adapted to reciprocation in 55 vertical guideways 80 attached to the conveyor frame. The cross head 79 is connected to a rocker arm 81 rotatable about a horizontal shaft 82 which is supported in suitable journal bearings 83 depending from the conveyor frame 46. Fixed to the shaft 82 adjacent the rocker arm 81, is a ratchet wheel 84 arranged to be engaged by a pawl 85 carried by the rocker arm 81 in such manner that reciprocation of the cross head 79 will cause 60 the rotation of the shaft 82. Devices are pro-

vided for the manipulation and control of this ratchet mechanism to vary the speed of rotation of the shaft 82, but as these devices form no part of the present invention, their description is not thought to be required. 70

Freely mounted upon the shaft 82 and connectable thereto by the sliding clutch members 86 and 87 respectively, are the winding drums 88 and 89 upon which are windable the feed ropes 90 and 91. The clutch members 86 and 87 are controlled by the clutch operating levers 92 and 93 which are connected together by the transverse pull rod 94 having operating handles 95 convenient to the hand of the operator at both sides of the machine. The pull rod 94 is provided with a projection 96 adapted to engagement with suitably positioned notches formed in a flange 97 depending from the conveyor frame, and coiled springs 98, mounted upon the clutch levers 92 and 93, resiliently press the rod 94 to hold the projection 96 in engagement with the said notches to prevent accidental shifting of the clutches 86 and 87. 80

The feed ropes 90 and 91 pass respectively around the guide rollers 99 and 100 which are fixed to the conveyor frame, and their free ends are attached to the opposite ends of the arcuate rail 44. When the shaft 82 is rotating, movement of the pull rod towards the right hand side of the machine will cause the clutch member 87 to engage the winding drum 89 to wind the feed rope 91, and as the drum 88 is free to permit the rope 90 to unwind, the conveyor frame will be drawn toward the left hand end of the rail 44. As the rearward end of the conveyor frame is held against the lateral movement by the pivot yoke 68, the gathering frame 74 will be moved over the floor of the mine towards the left to forcibly engage material lying upon the floor of the mine, and cause the bits 53 upon the conveyor chain 51 to engage said material and move it onto and along the conveyor trough. 100

Should the material upon the mine floor be composed of blocks too large to be handled by the conveyor, or should the mass be composed of fragments so interlocked as to be immovable, the cutter bits 53 will cut a clearance for themselves in such material, thereby protecting the chain 51 from undue strains, and at the same time tending to break up such fragments or tear them from the mass. It is apparent that movement of the pull rod 94 in the opposite direction will actuate the drum 88 to wind the rope 90 and draw the gathering devices toward the right instead of toward the left as described. 105

In operation the machine, adjusted to the position illustrated in Fig. 2, is moved by its own power into a mine room and positioned adjacent the working face along which material has been dislodged to form a mass of broken coal lying upon the floor 110

of the mine. The feed mechanism is then actuated to swing the gathering end of the conveyor over to one side of the room, preferably the left hand side, as illustrated in Fig. 14, after which the conveyor adjusting mechanism is actuated to rotate the screw shafts 5 in the direction to elevate the rear end of the conveyor frame. As the conveyor frame rocks upon the bearing 45, the forward end of said frame will be lowered to cause the gathering frame 74 to rest upon the mine floor. The truck propelling mechanism is then actuated to move the machine forward, and force the gathering frame into the mass of material adjacent the face of the coal, as illustrated in Fig. 15. The feeding mechanism is then manipulated to swing the conveyor frame around the pivot 67 and move the gathering frame across the face to the position illustrated in Fig. 16. When all of the dislodged material is loaded, the conveyor will be returned to the central position illustrated in Fig. 3, and the adjusting mechanism again actuated to lower the rear part of the conveyor frame into a position suitable to clear low parts of the mine roof, at the same time elevating the gathering frame to a position which will clear the track switches, and other obstructions upon the mine floor, when the machine will be ready to travel to another room where the operation can be repeated.

The method of mining coal most commonly used consists in undermining the vein and blasting down the overhanging coal, depending on the force of the blast to break it into fragments of suitable size to be loaded into cars for transportation from the mine. The machines commonly used for undermining the coal form kerfs approximately five inches high and positioned as near to the bottom of the vein as is conveniently possible. Circumstances governing the operation of these undercutting machines cause the kerfs to extend at a slight angle with the bottom of the vein, leaving a more or less uneven layer of coal, varying in thickness from zero to four or five inches, adhering to the floor of the mine. The surface of the bottom coal is commonly very irregular, presenting ridges and offsets which tend to obstruct the movements of the gathering extension frame 74 over the floor of the mine. When, however, these irregularities of the bottom coal are encountered by the cutter bits 53 they are either sheared off or torn loose from the underlying stratum, thereby producing an even floor and reclaiming a considerable amount of coal which would otherwise be lost. It will be seen that a combined cutting and gathering action will be effected by the bits, as the machine moves forward into the coal, and this double action results in economy in production.

In order to produce the largest possible

percentage of lump coal, the amount of explosive is often so far reduced that masses of coal are shattered without being dislodged, and considerable labor is required to sufficiently loosen such a mass for loading. By raising the forward end of the conveyor the gathering frame 74 may be brought into contact with such shattered masses of coal, when the cutter bits 53 will engage the inter-laced fragments, throwing down the mass in suitable form to be gathered by the conveyor when again lowered into loading position. This illustrates further the double action of the mechanisms described in cutting and carrying out the coal.

While I have shown a particular arrangement and specific instrumentalities for accomplishing the results aimed at, it will be obvious that expedients other than those shown and equivalent mechanical devices may be adopted without departing from the range of my invention.

I claim:

1. In a loading machine the combination with a self-contained elongated conveyor, of a pivotal support positioned forward of the center of gravity of said conveyor upon which it may be rocked in any direction, means to rock said conveyor upon said pivotal support, and means to move said pivotal support transversely of the machine.

2. In a loading machine, the combination with a self-contained elongated conveyor, of a pivotal support positioned forward of the center of gravity of said conveyor upon which it may be rocked in any direction, a support positioned at the rear of said center of gravity comprising a transversely extending bar upon which said conveyor is laterally slideable, means connected with said last mentioned support to prevent lateral movement of the rear end of said conveyor and means to move said pivotal support transversely of the machine as and for the purpose set forth.

3. In a loading machine, the combination with a truck adapted to travel over the tracks of a mine, of an arcuate rail mounted upon the forward end of said truck and extending transversely thereof, a self-contained elongated conveyor having a pivotal bearing positioned forward of the center of gravity of the conveyor and adapted to engage said arcuate rail, a support positioned in the rear of said center of gravity comprising a transversely extending bar supported by said truck and, vertically adjustable relative thereto; means connected with said bar to prevent lateral movement of the rear end of the conveyor and means to move said pivotal support longitudinally of said arcuate rail.

4. In a loading machine, the combination with a self-contained elongated conveyor, of a pivot support positioned forward of the center of gravity of said conveyor upon which it may be rocked in any direction, a support

- positioned at the rear of said center of gravity comprising a transversely extending bar upon which said conveyor is laterally slideable, and means to vertically adjust said bar to rock said conveyor upon said pivot support. 5
5. In a loading machine, the combination with a wheeled truck, of an arcuate rail fixed to the forward end of said truck and extending transversely thereof, a transversely 10 extending vertically adjustable bar mounted on the rear part of said truck, a self-contained elongated conveyor laterally slideable upon said bar and having a rocking bearing upon said arcuate rail, means to prevent lateral movement of the rear end of said conveyor, and means to laterally move said conveyor along said arcuate rail. 15
6. In a loading machine, the combination with a wheeled truck, of an arcuate rail fixed to the forward end of said truck and extending transversely thereof, of a transversely extending vertically adjustable bar mounted on the rear part of said truck, a self-contained elongated conveyor laterally slideable upon said bar and having a rocking bearing upon said arcuate rail, means to prevent lateral movement of the rear end of said conveyor and power devices upon the conveyor frame adapted to move said conveyor laterally along said arcuate rail. 20
7. In a loading machine, the combination with a wheeled truck adapted to travel along a mine track, of a transversely extending arcuate rail fixed to the forward end of said truck, a transversely extending bar mounted on the rear part of said truck, a self-contained elongated conveyor slidably supported upon said bar and having a rocking bearing upon said arcuate rail, and power devices upon said truck adapted to bodily move the truck longitudinally of the track and to vertically adjust the transverse bar as and for the purpose set forth. 25
8. In a loading machine, the combination with a wheeled truck, of a transversely extending arcuate rail fixed to the forward end of the truck, a transversely extending bar mounted on the rear part of said truck, a self-contained elongated conveyor laterally slideable upon said bar and having a rocking bearing upon said arcuate rail, means to prevent lateral movement of the rear end of the conveyor, means to laterally move said conveyor along said arcuate rail, and power devices upon the truck adapted to vertically adjust either or both ends of said transverse bar as and for the purpose set forth. 30
9. In a loading machine, the combination with a supporting truck, an elongated self-contained conveyor supported thereon and comprising a laterally disposed trough and centrally disposed chain guides, an endless chain arranged to travel in said chain guides and having laterally projecting sockets with 35 renewable cutterbits secured therein and positioned and arranged to engage material in the conveyor trough and propel it therealong, gathering mechanism comprising an extension frame hinged to the forward end of the conveyor frame and adapted to rest upon and slide over the floor of a mine, chain guides in said extension frame adapted to guide said chain in a path adjacent the mine floor to cause said cutter bits to engage material on the mine floor and move it onto said conveyor trough, a pivotal support for said conveyor midway its length upon which it may be rocked in any direction, and means to rock the conveyor upon said pivotal support to lift said gathering mechanism clear of the floor preparatory to moving from one working place to another. 40
10. In a loading machine, the combination with an elongated self-contained conveyor having laterally disposed troughs and centrally disposed chain guides, an endless chain adapted to travel along the chain guides, laterally projecting sockets on the chain, cutterbits removably secured in the sockets in position to engage material in the troughs and propel it therealong, an extension frame hinged to the forward end of the conveyor, adapted to rest upon and slide over the floor of the mine, said extension frame having chain guides positioned and arranged to guide the cutter bits through a path adjacent the mine floor to engage material thereon and move it into the conveyor troughs, a pivotal support for said conveyor midway its length upon which it may be rocked in any direction, and means to move said pivotal support transversely of the machine to feed said gathering mechanism to the material which is to be loaded. 45
11. In a loading machine, the combination of a truck adapted to be moved over a mine floor, an elongated conveyor having a lateral trough and centrally disposed guideways in which travels an endless chain, sockets formed on said chain, cutter bits secured in said sockets and together constituting laterally projecting arms adapted to propel material along the trough, a vertically adjustable pivot mounting for said conveyor on said truck to permit horizontal movements of said conveyor, a second laterally movable pivot mounting for said conveyor on said truck to permit vertical movements of said conveyor, an extension frame hinged to the forward end of said conveyor and adapted to rest upon and slide over the floor of a mine, said extension frame having guideways whereby the chain may be guided along a path adjacent the mine floor in such position that the cutterbits will engage material lying thereon and move it onto said conveyor trough, a support for said conveyor midway its length, and means to rock said conveyor upon said support. 50

12. In a cutting and loading machine, the combination with a wheeled truck, of a transversely extending support at the forward part of said truck, a transversely extending support mounted upon the rearward part of said truck, a self-contained conveyor slideable upon said supports and adapted to gather material from a mine floor in advance of said truck and transport it to elevated discharge points in the rear thereof, cutting devices adapted to form a path for said conveyor in the material in advance of said truck, and pivotal devices arranged to hold the delivery end of said conveyor against horizontal movement relative to said truck.

13. In a cutting and loading machine, the combination with a wheeled truck, of a transversely extending support at the forward part of said truck, a transversely extending support mounted for vertical adjustment on the rearward part of said truck, a self-contained conveyor slideable upon said supports and adapted to gather material from a mine floor in advance of said truck and transport it to elevated discharge points in the rear thereof, cutting devices adapted to form a path for said conveyor in the material in advance of said truck, and vertically movable pivotal devices arranged to hold the delivery end of said conveyor against horizontal movement relative to said truck.

14. In a loading machine, the combination with a wheeled truck, of a transversely extending support at the forward part of said truck, a transversely extending support mounted for vertical adjustment at the rearward part of said truck, a self-contained conveyor slideable upon said supports and adapted to gather material from a mine floor in advance of said truck and transport it to elevated discharge points in the rear thereof, cutting devices adapted to form a path for said conveyor in the material in advance of said truck, a vertically movable pivotal device arranged to hold the delivery end of said conveyor against horizontal movement relative to the truck, and self-contained power devices upon the truck arranged to move said conveyor about its pivot.

15. In a cutting and loading machine, the combination with a wheeled truck, of a transversely extending support at the forward part of said truck, a transversely extending support mounted for vertical adjustment at the rearward part of said truck, a self-contained conveyor slideable upon said supports and adapted to gather material from a mine floor in advance of said truck and transport it to elevated discharge points in the rear thereof, cutting devices adapted to form a path for said conveyor in the material in advance of said truck, vertically adjustable devices arranged to hold the delivery end of said conveyor against horizontal movement relative to the truck, and self-contained power

devices upon the truck arranged to move said conveyor in any direction relative to the material to be loaded.

16. In a machine of the class described, the combination of a support movable over a mine floor, a frame pivoted for vertical movement on a pivot laterally shiftable on said support, an independent vertically adjustable pivotal support for said frame to permit horizontal movement, conveying mechanism on said frame, means for tilting said frame in vertical planes, and independent means for swinging said frame in horizontal planes.

17. In a machine of the class described, the combination of a support movable over a mine floor, a frame pivoted between its ends on said support for vertical movement, a track member on which said frame pivot is shiftable, an independent vertically adjustable pivotal support for said frame to permit horizontal movement of said frame and its first named pivot mounting, means for tilting said frame on its first mentioned pivot mounting, and independent means for shifting said frame and its pivot mounting laterally along said track member.

18. In a machine of the class described, the combination of a base adapted to be moved over a mine floor, a vertically adjustable support on said base, a frame pivotally mounted on said support for horizontal movement, coal handling mechanism carried by said frame, and a second laterally shiftable pivot member supported by said base on which said frame and its mechanism is mounted for vertical movement.

19. In a machine of the class described, the combination of a base adapted to be moved over a mine floor, a vertically adjustable support mounted on said base, a frame pivotally connected to said vertically adjustable support at one end extending forwardly of said base at the other end, coal handling mechanism carried by said frame, a second pivotal connection supporting said frame for universal rocking movement, and a trackway mounted on said base upon which said second pivotal support is laterally shiftable.

20. In a machine of the class described, the combination of a base adapted to be moved over a mine floor, a vertically adjustable trackway mounted on said base, a pivot mounting extending horizontally from said trackway, a frame mounted for horizontal movement on said pivot and resting upon said trackway, coal handling mechanism mounted on said frame, a second pivot mounting for said frame to permit vertical movement, and an arcuate trackway on said base supporting said second pivot mounting to permit lateral movement thereof.

21. In a machine of the class described, a base adapted to be moved over a mine floor or the like, an elongated conveyor frame disposed above said base and extending from the

floor level in advance of the base to a delivery point above and to the rear of the base, the forward end of said frame being adapted to be supported in operative position on the floor, the rearward portion of said conveyor projecting substantially beyond the base, means on the base to support the rear end of the frame for vertical swinging and lateral displacement and to bear the weight of the said end in all positions of the frame, and pivoting means for projecting extremity of the frame spaced rearwardly from said supporting means, said pivoting means being supported from the base and arranged to give the projecting end of the frame a free overhang.

22. In a machine of the class described, a base adapted to be moved over a mine floor or the like, an elongated conveyor frame disposed above said base and extending from the floor level in advance of the base to a delivery point above and to the rear of the base, the forward end of said frame being adapted to be supported in operative position on the floor, the rearward portion of said conveyor projecting substantially beyond the base, means on the base to support the rear end of the frame for vertical swinging and lateral displacement and to bear the weight of the said end in all positions of the frame, pivoting means for the projecting extremity of the frame spaced rearwardly from said supporting means, said pivoting means being supported from the base and arranged to give the projecting end of the frame a free overhang, and means to vertically adjust said supporting means and said pivoting means.

23. In a machine of the class described, a base adapted to be moved over a mine floor or the like, an elongated conveyor frame disposed above said base and extending from the floor level in advance of the base to a delivery point above and to the rear of the base, the forward end of said frame being adapted to be supported in operative position on the floor, the rearward portion of said conveyor projecting substantially beyond the base, means on the base to support the rear end of the frame for vertical swinging and lateral displacement and to bear the weight of the said end in all positions on the frame, a horizontally extending arm beneath the projecting end of said frame, said arm having a pivotal connection with the base to permit it to swing in vertical planes, and a vertical pivot connecting the extremities of said arm and said frame, said arm being so disposed as to give the projecting end of the frame a free overhang.

24. In a machine of the class described, a base adapted to be moved over a mine floor or the like, an elongated conveyor frame disposed above said base and extending from the floor level in advance of the base to a delivery point above and to the rear of the base,

the forward end of said frame being adapted to be supported in operative position on the floor, the rearward portion of said conveyor projecting substantially beyond the base, means on the base to support the rear end of the frame for vertical swinging and lateral displacement and to bear the weight of the said end in all positions on the frame, a horizontally extending arm beneath the projecting end of said frame, said arm having a pivotal connection with the base to permit it to swing in vertical planes, a vertical pivot connecting the extremities of said arm and said frame, said arm being so disposed as to give the projecting end of the frame a free overhang, and means to vertically adjust said supporting means and said horizontally extending arm.

25. In a machine of the class described, a base adapted to be moved over a mine floor or the like, an elongated conveyor frame disposed above said base and extending from the floor level in advance of the base to a delivery point above and to the rear of the base, the forward end of said frame being adapted to be supported in operative position on the floor, the rearward portion of said conveyor projecting substantially beyond the base, means on the base to support the rear end of the frame for vertical swinging and lateral displacement and to bear the weight of the said end in all positions of the frame, a horizontally extending arm beneath the projecting end of said frame, said arm having a direct pivotal connection with said support to permit it to swing in vertical planes, and a vertical pivot connecting the extremities of said arm and said frame, said arm being so disposed as to give the projecting end of the frame a free overhang.

26. In a machine of the class described, a base adapted to be moved over a mine floor or the like, an elongated conveyor frame disposed above said base and extending from the floor level in advance of the base to a delivery point above and to the rear of the base, the forward end of said frame being adapted to be supported in operative position on the floor, the rearward portion of said conveyor projecting substantially beyond the base, means on the base to support the rear end of the frame for vertical swinging and lateral displacement and to bear the weight of the said end in all positions of the frame, a horizontally extending arm beneath the projecting end of said frame, said arm having a direct pivotal connection with said support to permit it to swing in vertical planes, a vertical pivot connecting the extremities of said arm and said frame, said arm being so disposed as to give the projecting end of the frame a free overhang, and means to vertically adjust said supporting means and therewith said horizontally extending arm.

27. In a machine of the class described, an elongated conveyor frame extending from a

point at the supporting surface for the machine to a remote elevated point, a cutter arm forming a forward continuation of said frame, a continuous draft device traversing said frame and arm, and cutter bits carried by said draft device.

28. In a machine of the class described, a frame having elongated horizontal and upwardly extending portions, the horizontal portion being adapted to rest upon a mine floor, an endless draft device circulating longitudinally of said frame, cutter bits mounted on said draft device, and means for laterally moving said frame to engage the cutter bits at the horizontal frame portion in a mass of material to disrupt and gather the material and convey it to and along the upwardly extending frame portion for delivery to a receiving point.

29. In a machine of the class described, a frame having elongated horizontal and upwardly extending portions, the horizontal portion being adapted to rest upon a mine floor, an endless draft device circulating longitudinally of said frame, cutter bits mounted on said draft device, the frame having peripheral guides for said draft device whereby the cutter bits at the horizontal frame portion are sustained in freely projecting relation over the mine floor, and means for laterally moving said frame to engage the cutter bits at the horizontal frame portion in a mass of material to disrupt and gather the material and convey it to and along the upwardly extending frame portion for delivery to a receiving point.

30. In a machine of the class described, an elongated conveyor frame extending from a point at the supporting surface for the machine to a remote elevated point, a cutter arm forming a forward continuation of said frame, pivotal means connecting the frame and cutter arm and having a horizontal axis extending transversely of the frame and cutter arm, a continuous draft device traversing said frame and arm, and cutter bits carried by said draft device.

31. In a machine of the class described, an elongated conveyor frame extending from a point at the supporting surface for the machine to a remote elevated point, a cutter arm forming a forward continuation of said frame, a pivotal means connecting the frame and cutter arm and having a horizontal axis extending transversely of the frame and cutter arm, means to limit the pivotal movement of the cutter arm relative to the frame about said axis, a continuous draft device traversing said frame and arm, and cutter bits carried by said draft device.

In testimony whereof, I affix my signature.
NILS D. LEVIN.
